US00D930115S

(12) **United States Design Patent** (10) Patent No.: **US D930,115 S**
Städler et al. (45) Date of Patent: ** Sep. 7, 2021

(54) **HAND SHOWER FOR TRAVELLING PURPOSES**

(71) Applicant: **Neoperl GmbH**, Mullheim (DE)

(72) Inventors: **Georg Städler**, Mullheim (DE);
Wolf-Dieter Lacher, Mullheim (DE);
Jürgen Höppner, Mullheim (DE)

(73) Assignee: **Neoperl GmbH**, Müllheim (DE)

(**) Term: **15 Years**

(21) Appl. No.: **35/507,366**

(22) Filed: **Mar. 8, 2019**

(80) **Hague Agreement Data**

Int. Filing Date: **Mar. 8, 2019**

Int. Reg. No.: **DM/202541**

Int. Reg. Date: **Mar. 8, 2019**

Int. Reg. Pub. Date: **Sep. 6, 2019**

(51) **LOC (13) Cl. 23-01**

(52) **U.S. Cl.**

USPC **D23/223**

(57) **CLAIM**

The ornamental design for a hand shower for travelling purposes, as shown and described.

DESCRIPTION

1., 2., 5., and 7. Hand shower for travelling purposes

1.1 : Top

1.2 : Perspective

1.3 : Bottom

1.4 : Perspective

1.5 : Left

1.6 : Front

1.7 : Right

1.8 : Back

2.1 : Top

2.2 : Perspective

2.3 : Bottom

2.4 : Perspective

2.5 : Left

2.6 : Front

2.7 : Right

2.8 : Back

5.1 : Perspective

5.2 : Perspective

5.3 : Right

5.4 : Front

5.5 : Top

5.6 : Back

5.7 : Bottom

5.8 : Left

7.1 : Perspective

7.2 : Perspective

7.3 : Back

7.4 : Bottom

7.5 : Left

7.6 : Right

7.7 : Top

7.8 : Front

The broken lines represent portions of the hand shower for travelling purposes in which the design is embodied that form no part of the claimed design.

1 Claim, 32 Drawing Sheets
